UNITED STATES PATENT OFFICE.

HENRY A. SEYMOUR, OF WASHINGTON, DISTRICT OF COLUMBIA.

ELECTRIC-ARC LAMP.

SPECIFICATION forming part of Letters Patent No. 574,117, dated December 29, 1896.

Application filed June 30, 1896. Serial No. 597,612. (No model.)

To all whom it may concern:

Be it known that I, HENRY A. SEYMOUR, of Washington, in the District of Columbia, have invented certain new and useful Improvements in Arc-Lamps; and I do hereby declare the following to be a full, clear, and exact description of the invention, such as will enable others skilled in the art to which it appertains to make and use the same.

10 My invention relates to an improvement in arc-lamps, and especially to that type of lamps which are operated by alternating currents.

Heretofore many attempts have been made to produce an arc-lamp for operation with an alternating current, and while a measure of success has been attained with lamps constructed to burn a short arc no one has as yet succeeded in providing an alternating-current lamp capable of establishing and maintaining a long arc within an arc-inclosing globe. It is absolutely essential to the establishment of an arc between the two electrodes of an alternating-current lamp that their adjacent ends be first heated to such a degree as will result in the formation of a bridge of conducting carbonaceous vapor across the gap or space between them when separated. Without some provision for heating the adjacent ends of the electrodes when current is passed through an alternating-current arc-lamp they will chatter violently for a considerable length of time before it is even possible to establish and maintain a short arc, and this is due to the fact that as a rapidly-alternating current is sent through the cold electrodes the current falls to zero so rapidly that the carbons cannot be maintained separated for a sufficient length of time to insure their being heated to such a degree as will insure the maintenance of an arc between them.

40 Hence the slight arc formed between the cold carbons is rapidly established and broken, resulting in a rapid and violent chattering of the carbons and regulating mechanism, which continues until the ends of the carbons have become sufficiently heated to insure the production of a conducting bridge of carbon vapor across the gap or space between them, and then, and not until then, is a persisting arc established.

The operation of alternating-current arc-

lamps as heretofore constructed has been attended by a constant hissing of the arc and buzzing of the regulating mechanism, which has proved so annoying and objectionable as 55 to have very largely restricted their use.

Attempts have been made to overcome the difficulties above set forth by so constructing the regulating mechanism that it would operate to very slowly separate the feeding carbon 60 from the non-feeding carbon and thus insure the establishment of a persisting arc between them; but lamps so constructed proved inefficient and defective in their operation for two reasons. First, the application 65 of means to the regulating mechanism for retarding the initial separating movement of the feeding carbon operated to deprive the regulating mechanism of that delicate and sensitive action which is essential to the 70 proper regulating and feed of the carbon and to the maintenance of a persisting arc, and, second, by imposing upon the regulating mechanism the duty of separating the carbons and establishing and drawing a long arc, it 75 rendered it impossible to maintain such a relation between the core and solenoid or armature and helix of the regulating mechanism as would insure its prompt and sensitive action in regulating and feeding the carbon. 80

The object of my invention is to provide an arc-lamp of such construction that the function of slowly separating the carbons and gradually drawing the arc to any desired length shall be performed by mechanism 85 associated with and acting upon the lower or non-feeding carbon, while all the functions necessary to the regulation and feeding of the carbons shall be performed by mechanism associated with and acting upon the feeding carbon.

A further object is to provide means for preventing the rapid vibration of the carbons or of the regulating mechanism when the lamp is in operation. A further object is to provide 95 an improved construction and arrangement of parts for supporting an arc-inclosing globe.

With these ends in view the invention consists in certain features of construction and 100 combinations of parts, as will be hereinafter described, and pointed out in the claims.

In the accompanying drawings, Figure 1 is a view, partly in vertical section and partly in side elevation, of an arc-lamp embodying my invention; and Figs. 2 and 3 are detailed views of the dash-pot.

A represents the lamp-floor, from which is suspended the supporting-bracket B, which is insulated from the floor and is strengthened and stiffened by means of the short bracket-arm *a* and ring *b*, said parts being either cast in a single piece or made separate and fastened together in any desired manner.

C is a solenoid supported in the lower end of bracket B. To the core D of the solenoid is attached a carbon-holding socket *c*, which is insulated from the core at *d*. A spiral spring E serves to uphold the core and the lower carbon F'. Helix G is composed of conductor of comparatively low resistance which is connected at one end to socket *c* by the flexible conductor *g*, while its opposite end is electrically connected at *f* with bracket B. To the under side of the solenoid is secured a dash-pot II, which is illustrated in detail in Figs. 2 and 3. Piston-rod *g* of the dash-pot is connected to core D. Piston II' is provided with an adjustable screw-valve II², by means of which the speed of the piston throughout its downward stroke may be retarded to any desired extent. In order to insure a prompt and quick upward movement of the core and lower carbon, piston II' is provided with any desired number of passages *h'*, through which extend the stems *h*, which are secured at their lower ends to an annular ring-valve II³, which seats over and closes the passages *h'*. Each one of the stems *h* is encircled by a spiral spring *h*², which is seated at one end on the top of the piston and at its opposite end against a collar or head on the upper end of the stem. By this construction of dash-pot the movement of the lower carbon may be retarded and made very slow and gradual throughout the entire downward movement, while its upward movement will be quick and prompt.

I is a shunt-solenoid, its helix *i* being composed of fine wire of comparatively high resistance and electrically connected at its opposite ends with opposite binding-posts J J' of the lamp. This solenoid is supported above the floor by brackets *i*' or in any other desired manner.

I' is a hollow core having a diamagnetic tube I², secured to its lower end. A spider I³ is attached to the lower end of tube I², and to its outer rim are adjustably secured the lower ends of spiral springs I⁴, which are secured at their upper ends to the lower head of the solenoid. The drawings illustrate only two springs, while four or more may be employed and arranged at equal distances apart around the tube I². A tubular carbon rod or holder K, passes down through the hollow core and tube and through the floor of the lamp, it being encircled by an annular ring-valve K', which is seated upon the lamp-floor

and snugly fits the carbon-rod and serves to prevent the passage of gases into the casing containing the regulating mechanism.

L is a ring-clamp surrounding the carbon-holder and resting upon the ring-valve K'. This clamp is provided with a groove *k*, into which projects the finger *k'* of the lifter *l*². A stop *k*² limits the upward movement of the ring-clamp.

Within the hollow carbon rod or holder is a piston *l*, which is suspended by a rod *l'*, attached at its upper end to the top of the casting, whereby the carbon-rod and piston serve as a dash-pot to steady the action of the upper carbon. To the carbon-rod is attached by a ball-and-socket joint *l*² a cover M, which is constructed with a socket *m*, in which the feeding carbon F is secured by a set-screw *m'*. Arc-inclosing globe N is connected to cover M by means of set-screws *n*, which bear against the beveled surface *n'* on the globe and thereby force its ends into snug engagement with the cover. Instead of employing the fastening devices shown any suitable means may be used for securing the globe to the cover, so as to form practically an air-tight joint between them. The cover is provided with a safety-valve *n*² to prevent an excess of pressure within the globe. The bottom of the arc-inclosing globe is provided with a cover O, having an opening *o* formed therein, through which the lower carbon F' passes and within which it snugly fits.

Outer globe P is provided at its upper end with an outwardly-flaring flange *p*, which seats against the inclined face of a bearing *p'*, formed on the under side of the floor of the lamp or connected therewith. The globe is secured in place by means of the set-screws *p*² and is rendered tight by the metal strip *p*³ fitting snugly against the bearing *p'*. Set-screws *p*³ by their engagement with the inclined surface on the flange *p* operate to force the latter into snug contact with the inclined seat *p'*. Casing Q may be made of a single casting or may be provided with suitable doors or covered openings and is secured to the lamp-floor by screws *q*.

The operation of the lamp is as follows: When no current is passing through the lamp, its carbons are very slightly separated, the upper carbon, together with the arc-inclosing globe, being upheld by the springs I¹, which serve to lift the hollow core and lifter and cause the ring-clamp to grip the carbon-rod and support it in its raised position. When current is passed through the lamp, it first flows through the helix of the shunt-solenoid and energizes the latter sufficiently to cause it to pull down the hollow core and upper carbon and to bring the two carbons into contact. Immediately the carbons are brought into contact practically the entire current will flow from binding-post J through the lamp-floor A, carbon-holder K, carbons F F', solenoid C, bracket B to the binding-post J', and from thence to line. The passage of the

current through the lamp will operate to weaken the shunt-magnet and permit the springs k^4 to lift the upper carbon and thereby establish an arc between the two carbons; but this arc will be very short, owing to the fact that the stop k^3 will so limit the upward movement of the upper carbon that it will be separated but a very slight distance from the lower carbon. At the same time the passage of the current through the carbons, when brought into contact, will energize solenoid C and cause it to pull down its core and lower carbon supported by it; but the downward movement of the lower carbon is so retarded by the dash-pot H as to cause it to separate very slowly and gradually from the upper carbon, and hence it continues to descend until it has drawn an arc of any desired length. The very slight initial separation of the carbons, due to the upward movement of the feeding carbon, operates to insure such a resistance to the passage of the current as will result in the rapid heating of the ends of the carbons without interrupting the circuit and extinguishing the arc, and the slow and gradual descent of the lower carbon will insure the drawing of an arc of any desired length without extinguishing it.

Instead of operating in the manner above described the parts may be so adjusted that the carbons will be in contact when no current is passing through the lamp. Now on the passage of current through the lamp the lower carbon will be drawn down very slowly, with the result that an exceedingly minute arc will be first established between them, which arc will suffice to heat their adjacent ends and insure the maintenance of the arc, which will gradually be elongated until it has been slowly drawn to any desired length. An arc of normal length having been thus established between the two carbons, it will continue to burn, and as it grows longer its resistance will increase, with the result that an increased amount of current will flow through the shunt-solenoid, and so strengthen it until it will pull down its core and cause the upper carbon to feed through the ring-clamp, and thus maintain a normal length of arc.

Owing to the fact that the pull of the shunt-magnet varies with and is at all times dependent upon the resistance of the arc, the regulating mechanism is so constructed and adjusted that not until an arc of normal or predetermined length has been established by the downward movement of the lower carbon will such an equilibrium of forces be established between the shunt-magnet and the opposing springs as will insure that delicate and sensitive automatic adjustment and feed of the upper carbon which is necessary to the maintenance of a persisting arc of uniform length and brilliancy.

In order to prevent the rapid vibration of the upper carbon and the fluctuation of the arc and light produced by it, a dash-pot formed of a piston working in the hollow car-

bon-rod is employed to slightly retard and check the upward-and-downward movement of the feeding carbon, and still permit of a sufficiently prompt and sensitive action of the regulating mechanism to insure a steady and uniform light.

As an additional means for steadyng the arc and for preventing any vibrations of the feeding carbon and regulating mechanism, the shunt-magnet is provided with a closed diamagnetic conductor I, which preferably consists of a closed tube of copper which may be located either inside or outside of the fine-wire helix. On the passage of an alternating current through a solenoid the rapid rise and fall of the current will induce "extra" currents in the coils of the helix, which, acting on the core, will cause it to vibrate and impart very slight and rapid fluctuations to the arc. To obviate this trouble, a closed diamagnetic conductor I is placed either inside or outside of the helix and serves to suppress such extra current and thus shield and protect the core against the influences of such rapid magnetic impulses, and enable a steady and reliable arc to be maintained.

In the event the arc should be extinguished from any cause the lower solenoid will be de-energized, with the result that the lower carbon will be instantly raised by the spiral spring D and brought into contact with the upper carbon, the dash-pot being constructed to permit of the quick upward movement of its piston, thus instantly re-establishing the arc between them.

By mounting the arc-inclosing globe in the manner shown the escape of gases from the globe and the ingress of outer air thereto may be prevented by means of a cover which will permit of greater freedom of action to the carbon passing through it than is possible when the carbon is fed through the top of the globe for the following reason.

It has been practically demonstrated that the specific gravity of the gases generated within an arc-inclosing globe is slightly less than that of the outer air, and hence the tendency of such gases is to rise and escape through the opening formed between the carbon and the walls of the hole in the cover through which the carbon is fed. Hence in lamps as heretofore constructed it has been found necessary to form a tight joint around the upper and feeding carbon to prevent the escape of gases and ingress of outer air, and the means resorted to for producing such tight joint have been found to more or less interfere with the adjustment and feed of the carbon. By inverting the globe and providing its upper end with a tight imperforate cover, which will prevent the rise and escape of gases from the globe and also the fall of the outer air into its upper end, the gases generated therein will be confined within the globe and form a seal around the arc, which will be preserved by a cover applied to the lower end of the globe and having a hole

formed therein of such size that the lower carbon may freely slide therein.

By connecting both the upper carbon and the arc-inclosing globe to the carbon rod or holder by a ball-and-socket joint and causing the lower carbon to serve as a guide for the lower end of the globe and upper carbon the two carbons are retained in alinement and ample lateral movement in all directions is afforded the globe to provide for any irregularities that may exist on the surface of the lower carbon.

To trim the lamp, the set-screws p^2 are loosened and the outer globe P is lowered and suspended from bracket B by means of the sliding connection S , connected at one end with the metal strip p^3 and engaging the bracket at its forward end.

While the lamp is especially adapted for use with an alternating current on constant-potential circuits, it is evident that it may be used with a straight current and also may be used on constant-current circuits.

Having fully described my invention, what I claim as new, and desire to secure by Letters Patent, is—

1. In an arc-lamp, the combination with its carbons and means for retaining them slightly separated when no current is passing through the lamp, of means for automatically bringing the carbons into contact and means for separating them very slightly when current is sent through the lamp and means for slowly and gradually separating the non-feeding carbon from the feeding carbon and thereby slowly drawing the arc to any desired length, substantially as set forth.

2. In an arc-lamp, the combination with the lower and non-feeding carbon, of means for slowly and gradually separating it from the upper and feeding carbon and thereby drawing an arc of any desired length, of means for permitting of the quick upward movement of

the lower carbon when the arc is extinguished, substantially as set forth.

3. In an arc-lamp, the combination with its carbons, of an arc-inclosing globe constructed and arranged to be fed downward with the upper carbon, and provided with a cover at its lower end within which the lower carbon snugly fits, substantially as set forth.

4. In an arc-lamp the combination with the carbon-holder and the upper and lower carbons, of an arc-inclosing globe connected with and suspended from the carbon-holder, said globe being provided at its lower end with a cover in which the lower carbon snugly fits, substantially as set forth.

5. In an arc-lamp the combination with the carbon-holder, and lower and non-feeding carbon, of an arc-inclosing globe and feeding carbon, suspended from the carbon-holder by a universal joint, said globe being provided with a cover on its lower end having an opening in it through which the lower carbon passes, substantially as set forth.

6. In an arc-lamp the combination with the carbon-holder, lamp-floor and annular valve encircling the carbon-holder and seating upon the lamp-floor, of a ring-clamp located over and adapted to rest upon said annular valve, substantially as set forth.

7. In an arc-lamp the combination with its carbons of an arc-inclosing globe suspended from its upper end, whereby its lower end is adapted to move laterally in any direction, the lower end of the globe being provided with a cover having an opening through which the lower carbon passes, substantially as set forth.

In testimony whereof I have signed this specification in the presence of two subscribing witnesses.

HENRY A. SEYMOUR.
